C. F. GRANZOW, JR

GARAGE DOOR HOLDER

Filed July 2, 1921

Charles F. Granzow, Jr. Inventor

By Whittmore Hubbard Whittmore &
Belknap Attorneys

UNITED STATES PATENT OFFICE.

CHARLES F. GRANZOW, JR., OF DETROIT, MICHIGAN.

GARAGE-DOOR HOLDER.

Application filed July 2, 1921. Serial No. 482,082.

To all whom it may concern:

Be it known that I, CHARLES F. GRANZOW, Jr., a citizen of the United States of America, residing at Detroit, in the county 5 of Wayne and State of Michigan, have invented certain new and useful Improvements in Garage-Door Holders, of which the following is a specification, reference being had therein to the accompanying drawings.

10 This invention relates to door holders, and more particularly to devices for holding garage doors in a desired open position.

15 The invention consists in the structural features and arrangement of parts herein- 15 after described and illustrated in the accom- panying drawing, wherein:

20 Fig. 1 is a horizontal sectional view looking upwardly showing a garage door and its frame, said door being equipped with the improved holding means, the open position 20 of the door and corresponding adjustment of the holding means being indicated in dash lines;

25 Fig. 2 is a fragmentary view in side elevation of the door showing the adjustment of the holding device when the door is open;

Fig. 3 is a cross-section view taken on line 3—3 of Fig. 1;

30 Fig. 4 is a cross-section on line 4—4 of Fig. 1;

Fig. 5 is a detail view showing the pivotal mounting of one end of the holder rod.

35 In these views, the reference character A designates a door hinged in the usual manner at A' to one of the frame uprights B. To the top cross piece B' of the frame there is pivotally secured one end C' of a holder rod C extending horizontally toward the free edge of the door in substantial parallelism to the latter, and having its free end 40 upturned as indicated at C². Preferably the pivotal mounting of said rod is established by forming an eye upon the end C' of the rod, and engaging in said eye a headed bolt or screw D, taking into the cross piece B'. The rod C engages a latch member E having the nature of a plate intermediately bent at substantially a ninety degree angle, and pivotally depending from a bolt F, passing 45 through and rigidly connected to the door A, said latch member being mounted preferably at a distance both from the free edge of the door and from the hinged edge

thereof. Below its intermediate angle said plate E is formed with an aperture G 55 through which the rod C is freely passed.

Considering the operation of the device as so far described: As the door A is swung open the latch plate E is caused to slide relative to the rod C toward the free end thereof, the relative positions of said rod and latch member when the door is fully open being indicated in dash lines in Fig. 1. No latch effect results from this relative movement accompanying opening of the door. When, however, the door is subjected to pressure tending to close the same, it is required of the latch plate E to slide relative to the rod C toward the inner or pivotal end thereof, such a relative movement tends to rock said latch member in the direction of the arrow in Fig. 2, thus tending to increase the inclination of the lower portion of the latch plate to the rod and causing the latch plate to bind upon the rod with a force increasing 70 proportionately to the force tending to close the door. Consequently in any desired open position of the door said latch member acts automatically to resist closing of the door until said member has been raised sufficient 75 to overcome the binding effect, as for example, to the position shown in dash lines in Fig. 2. To permit such raising of the latch member an elongated wire handle H is 80 swung from the lower end of the plate E, the lower end of said handle forming a ring 85 which may be engaged with a nail or screw H' in the door A to maintain the latch member in its raised inoperative position if desired.

90 Adjacent the latch member E there is pivoted upon the door A, beneath the rod C, a releasing member I for said rod, the pivot of said releasing member being indicated at I'. Adjacent to the member I, above the pivot I', a pin J is affixed in the door A between the outer end of the rod C and said releasing member. When said releasing member is in the vertical position indicated in dash lines in Fig. 2, the rod C is held sufficiently raised to throw the latch member E to its inoperative position also indicated in dash lines in Fig. 2. When the releasing member I is tilted as indicated in full lines in Fig. 2, the free end portion of the rod C 100 is supported by the latch member E and the

latter is effective to bind upon said rod to resist closing of the door. As the door is being opened, the sliding movement of the rod C relative to the releasing member I is inward or toward the hinged edge of the door, and the effect is to tilt the releasing member I to its position indicated in full lines in Fig. 2 so as to leave the latch member operative to prevent closing of the door when the latter has been opened to the desired extent. When it is desired to close the door, it is necessary to exert a slight upward pressure upon the handle member H shifting the latch member to its inoperative raised position and correspondingly lifting the free end of the rod C, gravity will then swing the release member I to its vertical position to maintain the raised position of the rod C, and the released position of the latch member E while the door is being closed. During closing of the door the sliding movement of the rod C relative to the releasing member I is outward tending to maintain said releasing member pressed against the pin J in a vertical position. Thus it is seen that the described latch member requires no adjustment whatever to permit opening of the door to any desired position, and tends to automatically engage the rod C to maintain such position. To permit closing of the door there is required only an initial adjustment of the handle H. The released position of the latch member being then maintained as the door is closed by the holding device I.

What I claim as my invention is:

1. In a device of the character described, the combination with a hinged door and its frame, of a rod pivoted upon said frame and extending substantially in a horizontal direction and substantially parallel to the door, and means for holding said door in any desired position of adjustment comprising a gravity actuated latch member pivoted upon the door and having a portion apertured for engagement by said rod and normally inclined to said rod and said latch member binding upon the rod to frictionally resist relative sliding of the rod and latch member in one direction.

2. In a device of the character described, the combination with a hinged door and its frame, of a rod pivoted upon said frame and extending substantially in a horizontal direction and substantially parallel to the door, means for holding said door in any desired position of adjustment comprising a gravity actuated latch member pivoted upon the door and having a portion apertured for engagement by said rod and normally inclined to said rod and said latch member binding upon the rod to frictionally resist relative sliding of the rod and latch member in one direction, and means for manually shifting said latch member angu-

larly out of binding engagement with the rod.

3. In a device of the character described, the combination with a hinged door and the frame thereof, of a rod pivoted upon said frame and extending horizontally in substantial parallelism with the door, means for holding said door in any desired position of adjustment comprising an intermediately bent gravity actuated latch member pivoted at its upper end upon the door above said rod and frame below the bend thereof with an aperture engaging said rod, said latch member binding upon the rod to frictionally resist relative sliding of the rod and latch member in one direction, and means for angularly shifting said latch member to a non-binding position.

4. In a device of the character described, the combination with a hinged door and the frame thereof, of a rod pivoted upon said frame and projecting toward the free edge of the door adjacent to the latter, means for holding said door in any desired position of adjustment comprising a gravity actuated latch member carried by the door and frictionally engageable with said rod, a pivotal member mounted upon the door beneath said rod supporting the rod in non-latching position, and means for angularly adjusting said pivotal member to release the rod.

5. In a device of the character described, the combination with a hinged door and its frame, of a rod pivoted upon said frame and extending substantially in a horizontal direction and substantially parallel to the door, and a gravity actuated latch member for holding said door in any desired position of adjustment comprising an angle plate pivoted at one end upon the door and having one of its inclined sides apertured for engagement by said rod, said latch member binding upon the rod to frictionally resist relative sliding of the rod and latch member in one direction.

6. In a device of the character described, the combination with a door and its frame, of means for normally holding said door in any desired position of adjustment comprising a latch rod pivoted upon one of said elements and a coacting pivotal latch upon the other having a portion normally inclined to said rod and apertured for engagement therewith, said latch member normally frictionally resisting the movement of said rod in one direction, means for raising said normally inclined latch member to a non-resisting position, and means engageable with said rod and automatically operated for maintaining said latch member in non-resisting position.

7. In a device of the character described, the combination with a hinged door and the frame thereof, of a rod pivoted upon said frame and projecting towards the free edge

of the door adjacent to the latter, means for holding said door in any desired position of adjustment comprising a gravity actuated latch member carried by the door and frictionally engageable with said rod, and means directly engageable with said latch member for adjusting the same to an unlatched position, and means engageable with said rod for maintaining said latch member in said unlatched position when said latch adjusting means is released. ¹⁰

In testimony whereof I affix my signature.

CHARLES F. GRANZOW, JR.
